APPARATUS FOR FOLIATING WIRE
RIBBON LEADSPaul A. Dell, Highland Heights, Ohio, assignor to
General Electric Company, a corporation of
New York

Application September 1, 1951, Serial No. 244,819

5 Claims. (Cl. 80—31.1)

1

This invention relates generally to lamp making machinery, and more particularly to apparatus for foliating or forming a flat ribbon portion into a lead-in wire for a vitreous bulb.

In sealing a lead-in wire or conductor into a vitreous bulb, it is necessary either that the conductor have the same coefficient of expansion as the vitreous portion into which it is sealed, or that it be proportioned to yield to the vitreous portion during the unequal expansion of the two. Where the vitreous bulb is made of transparent quartz or fused silica, the first method is inapplicable. The reason for this is that quartz has a very high fusing temperature and its coefficient of thermal expansion differs greatly from that of all suitable metals. Moreover, the choice of metals is seriously restricted because very few can be worked at the high temperature necessary for fusing into quartz. Accordingly recourse must generally be had to the second method involving the use of foil or ribbon seals.

With a quartz bulb, a hermetic or vacuum type seal can be formed with molybdenum sheets or ribbons provided that the ribbon is sufficiently thin. The coefficient of expansion of molybdenum is nearly ten times that of quartz so that stresses may be set up in the latter owing to the differential expansion between them. Provided the metal is very thin and properly bonded to the quartz, such stresses may be insufficient to crack the quartz. In other words, the metal having become bonded to the quartz at a relatively high temperature, will merely go into tension when the bulb cools but will not rupture nor crack the quartz.

Up to the present time molybdenum ribbon seals have generally been produced by welding together thin strips of foil or ribbon to wires of suitable lengths. The molybdenum foil is cut into strips a few millimeters wide and of the proper length required for the seal, and thicker molybdenum wires are welded to each end of a strip to form the current connections. The ribbon or foil is preferably etched in an electrolytic bath which cleans the surface thoroughly and roughens it slightly. The bath also dissolves away some of the metal so that feather edges are produced which assists in preventing leakage around the seal.

It will readily be understood that molybdenum ribbon lead wires made from welded sections require considerable manual labor and are necessarily very expensive. Moreover a considerable amount of wastage occurs due to the difficulty of controlling the welding temperature. In addi-

tion, even though the welded ribbon leads appear satisfactory upon visual inspection, very often, when they are subsequently assembled into lamps, it is found that they break at the welded joints and the lamps are worthless. Such subsequent breakage during manufacture appears to be due to the embrittlement and to the continuities occurring in the ribbon leads by reason of the two welds; it will be realized that the discontinuities are not only mechanical but also thermal and electrical. By eliminating these discontinuities, not only may the ribbon lead be made stronger, but it may also have a higher current carrying capacity.

15 In the copending U. S. patent application No. 244,818, of Edward B. Noel jointly with myself, filed Sept. 1, 1951, entitled "Ribbon Lead Construction," and assigned to the same assignee as the present invention, there is described a ribbon lead formed from a single piece of wire. That lead comprises two round molybdenum wire portions forming the ends, and an intermediate flattened portion through which the seal to the quartz is made. The lead is made by longitudinally rolling a piece of molybdenum wire between a pair of hardened cylindrical rolls. Such a ribbon lead has the very decided advantages that the cross-section changes gradually from a circular one into a flattened elliptical one without the occurrence of any sharp discontinuities. Thus the concentrations of stress which occur with ribbon leads made up of welded sections, are eliminated and the resulting seal is not only stronger but able to withstand a higher temperature and to carry a heavier current without danger of burning out or cracking the quartz.

20 The general object of the present invention is to provide an improved apparatus for foliating a round wire.

25 Another object of the invention is to provide a new and improved apparatus for rolling a flattened and longitudinally extended portion into a piece of wire.

30 The specific object of the invention is to provide a mechanism for producing the rolled molybdenum wire ribbon leads described in the previously mentioned copending application of Noel et al., wherein the foliated portion of the lead is made by flattening and stretching the metal in a direction parallel to the axis of the wire in order to achieve a longitudinal crystal orientation throughout the round and the flat portions of the lead without any sudden discontinuities.

35 In accordance with the invention, a one piece

ribbon lead is made by holding a short length of wire, preferably under some tension, between a pair of hardened rolls which are rocked backwards and forwards through a gradually increasing arc. The rolls are mounted in a pair of opposed semi-cylinders journaling in open bearing shoes. Means are provided for forcibly sliding one bearing shoe towards the other, thereby to squeeze the wire between the rolls, and means are also provided for automatically rocking the semi-cylinders through the gradually increasing arc required for the operation.

For further objects and advantages and for a better understanding of the invention, attention is now directed to the following description and accompanying drawings. The features of the invention believed to be novel will be more particularly pointed out in the appended claims.

In the drawings:

Fig. 1 is a pictorial view of a one piece molybdenum ribbon lead such as is produced by the mechanism of the present invention.

Fig. 2 is a pictorial view of a high pressure mercury vapor quartz arc tube constructed with one piece molybdenum ribbon seals.

Fig. 3 is a pictorial view of an apparatus for making one piece molybdenum ribbon leads and constituting a preferred embodiment of the invention, and in which certain portions have been broken away for greater clarity.

Fig. 4 is a fragmentary pictorial view of one of the semi-cylinders and its roll.

Fig. 5 is a simplified diagram, schematic in form, of the control system utilized in conjunction with the mechanism of Fig. 3.

Fig. 6 shows a hydraulic cylinder alternatively as the driving means for the mechanism of Fig. 3 in lieu of the reversing screw arrangement shown therein.

Fig. 7 shows the gripping means or tension pliers which may be utilized for holding a length of wire between the rolls of the mechanism.

Figs. 8a, b, c and d are illustrative of successive steps in rolling a flat portion into a molybdenum wire for making a one piece ribbon lead.

Referring to Fig. 1, there is shown a rolled one piece ribbon lead 1 as made by the mechanism of the present invention. The lead comprises cylindrical end portions 2 and 3 which are actually the wire from which the intermediate foliated or ribbon-like portion 4 was formed by rolling the wire forward and backward under tension between a pair of hardened rolls. The maximum permissible thickness A of the foliated or ribbon portion 4 depends upon the material of the lead and also upon the vitreous portion into which it is to be sealed. For a molybdenum seal into quartz, the optimum thickness is approximately .0005 inch; thicknesses greater than .001 inch may give trouble with leaks, whereas thicknesses less than .0005 inch are fragile and lack current carrying capacity. The width B of the ribbon portion depends upon the current to be carried and, in practice, varies from about 1 to 10 millimeters. The length C of the ribbon portion depends upon the size of the seal, the temperature conditions of the lamp in operation, and the difference in the expansion coefficients of the lead material and of the glass or surrounding quartz. With copper sealed in glass, for example, the length C may be as little as 1 millimeter. With very high temperature mercury arc quartz tubes on the other hand, the seal may be as long as 25 millimeters. For a moderately high pressure mercury arc lamp such as is illus-

trated in Fig. 2, the width B and the length C of the seal may be approximately 2 and 5 millimeters respectively.

Ribbon leads of the type illustrated in Fig. 1 may be used generally for effecting a seal into a vitreous bulb where it is not feasible to rely on matching the expansion coefficient of the lead metal and of the vitreous bulb for obtaining a hermetic seal. As an illustrative example, there is shown in Fig. 2 a high pressure mercury vapor arc tube 5 comprising a quartz envelope 6, into the opposite ends of which are sealed a pair of main electrodes 7 and 8 and an auxiliary starting electrode 9. These electrodes comprise the ribbon leads 1 which have been described, one cylindrical end serving as the external connection and the other end supporting the electrode proper within the arc tube. In the case of the main electrodes 7 and 8, small tungsten slipover coils 10 and 11 are mounted on the inner ends of the lead and enclose a small sliver of thorium metal which serves to increase the electron emission of these electrodes. The ribbon leads may be sealed into the quartz tube by locating them inside a length of cylindrical quartz tubing corresponding to the bulb 6, heating the ends thereof in a reducing atmosphere, and thereafter collapsing the ends by mechanical means, so as to lock the foliated portion of the ribbon lead in the quartz. Alternatively, the seals may be made by vacuum collapse of short lengths of quartz tubing about the ribbon leads, and thereafter fusing these lengths to quartz bulbs.

The mechanism by means of which the ribbon leads are made from molybdenum wire is illustrated in Fig. 3. A length of molybdenum wire is located vertically between a pair of hardened rolls 15 and 16 mounted in steel semi-cylinders 17 and 18, which are journalled in bronze bearing blocks or shoes 19 and 20. The forward faces of the bearing blocks 19 and 20 are shaped to a cylindrical curvature in order to serve as bearing surfaces for the semi-cylinders 17 and 18. The bearing shoes are fastened to cross pieces 21 and 22, the former being slidably mounted on a pair of guide rods 23 and 24. Cross piece 22, the standard 25 and the guide rods supported thereby are rigidly fastened to a frame member 26 which serves as a main support for the apparatus. The movable cross piece 21 may be forced against the fixed standard 22 by means of an air cylinder 27 whereof the piston 28 is directly connected through the rod 29 to the movable cross piece.

The hardened rolls 15 and 16 operate on the wire compressed between them, through a rocking movement. This rocking movement is imparted to the steel semi-cylinders 17 and 18 through the cranks 30 and 31 which are attached to them on one side, as by welding. The cranks 30 and 31 are swung up and down by means of a screw crosshead 32 to which they are linked by connecting rods 33 and 34. Crosshead 32 is reciprocated vertically by the two parallel lead screws 35 and 36 which are rotated by a reversible electric motor 37 geared thereto as shown at 38.

Where the ribbon leads are to be made of some relatively soft material such as copper or iron wire, the rolls 15 and 16 may be merely hardened steel cylinders. However where the ribbon leads are to be made of a very hard material such as molybdenum or tungsten, the rolls 15 and 16 may be cylinders of a cemented tungsten carbide sold commercially under the trade name "Carboloy." This material is very hard and strong in com-

pression but is relatively weak in tension. The mounting scheme, in accordance with the invention, utilizes these characteristics to the best advantage and maintains the rolls 15 and 16 under compressive stress only.

The mounting details may readily be seen in Fig. 4 from which it will be observed that the roll 15 is backed by some portion of the steel semi-cylinder 17 at all angles throughout its arc of rock. In transmitting the stress to the semi-cylinder, the tungsten carbide roll distributes it over a considerable area and thus the semi-cylinder can safely withstand it, even though made of steel having a much lower compressive strength than tungsten carbide. The steel semi-cylinder further distributes the stress over the face of the bearing shoe 19 having a yet greater bearing area and thereby allows the utilization therefor of a relatively soft material such as bronze. It will be appreciated that mating surfaces of steel and bronze provide an ideal combination from the point of view of ease of lubrication. The side plate 39 fastened to the bearing shoe, locates the semi-cylinders and the end of the crank 38 by means of a small pin 40 which enters the circular projecting portion 41 of the crank along the axis of rotation of the semi-cylinder. The tungsten carbide roll 15 fits in the semi-cylindrical cavity 42 in the semi-cylinder and may be welded or soldered in place. This arrangement retains the semi-cylinders in place when they are withdrawn one from the other; during the rolling operation, of course, the compressive stresses are taken up by the bearing shoes. The arrangement permits the application of compressive stresses in the range of 500,000 pounds per square inch to the molybdenum wire in order to roll a flat portion into it.

In the rolling operation, it is desirable that the arc of rock of the rolls be gradually increased as the middle portion of the molybdenum wire becomes flattened and elongated. It is also preferable that the pressure exerted on the rolls be likewise increased since the ribbon portion of the wire increases in width as it decreases in thickness. Thus the wire offers an increasingly greater bearing area against the rolls as it is gradually flattened, thereby requiring an increase in the compressive force in order to maintain the same pressure per unit area on the wire. The control system by means of which these operations are effected is schematically illustrated in Fig. 5.

Referring to Fig. 5, the arc of rock of the rolls is directly dependent on the throw or vertical displacement of crosshead 32, which in turn is controlled through the limit switches K-1 and K-2 mounted thereon. These limit switches close when they contact upper and lower limit tabs 50 and 51 which are mounted on the periphery of a rotatable cylinder 53. Cylinder 53 has been illustrated in developed form for greater clarity. The limit tabs 50 and 51 are stepped so as to provide a gradually increasing stroke to the crosshead 32.

The electric motor 37 is of a three phase type and is connected for energization from a three phase supply at the terminals 54, the phases being indicated by A, B, and C. As is well-known, the direction of rotation of such a motor may be reversed by interchanging two of the phase connections. This is done through the reversing switches K-3 and K-4, the former being the "down" switch and the latter the "up" switch. When switch K-3 is closed, motor 37 rotates so

as to move crosshead 32 down, whereas when switch K-4 is closed, the motor reverses so as to move the crosshead up. The operation of the reversing relays K-3 and K-4 is effected through control relays K-5, K-6, respectively.

The operation of the control system may be understood most readily by following the sequence of actions through one cycle of reversals between a set of limit switches. The operation is initiated by momentarily pressing start switch 55. This is equivalent to closing the upper limit switch K-1 and completes a circuit from phase A through conductor 56, switch 55, coil 57 of relay K-5, conductor 58, stop switch 59, and conductor 60 to phase B. Immediately, control relay K-5 operates and its holding contacts 61 close, so that the relay is thereafter held closed, independently of the starting switch 55 or of the limit switch K-1. The holding circuit is completed to phase A through the normally closed contacts 62 of relay K-6, and to phase B through conductor 58, stop switch 59, and conductor 60. When relay K-5 is energized, its lower contacts 63 close and energize coil 64 of the "down" reversing switch K-3 so that crosshead 32 begins its downward stroke.

The momentary closing of the start switch 55, or of the upper limit switch K-1 on subsequent strokes, also serves to energize ratchet relay K-7. This relay is arranged to rotate cylinder 53 intermittently by means of the pawl 65 to which its armature is linked, and the ratchet teeth 66 on the underside of cylinder 53, which the pawl engages. As a result, the cylinder is indexed through one position in the direction of the arrow 53', and the first pair of limit tabs 50 and 51 are brought into alignment with the limit switches K-1 and K-2.

The crosshead 32 continues its downward stroke until the lower limit switch K-2 strikes the first lower limit tab 51. A circuit is thereupon completed from phase A to phase B through the coil 67 of relay K-6. As soon as relay K-6 is energized, its normally closed contacts 68 open and break the holding circuit which had previously been holding relay K-5 energized. The normally closed contacts 69 of relay K-5 thereupon reclose, and a holding circuit for relay K-6 is completed through its normally open contacts 69 and the normally closed contacts 68 of relay K-5. Thereafter relay K-6 remains closed independently of the limit switch K-2 until the time when the normally closed contacts 68 of relay K-5 are opened. This occurs when the upper limit switch K-1 strikes the top limit tab 52 for the next reversal of the stroke. The circuit for energizing the control coil 70 of "down" relay K-4 is completed through the lower contacts 71 of relay K-6.

The stroke or throw of the crosshead 32 is thus determined by the location of the limit tabs 50 and 51. In the preferred embodiment of the invention, these limit tabs are disposed stepwise for a gradually increasing stroke so as to correlate the rocking arc of the rolls to the gradually increasing length of the flat or ribbon portion of the lead.

In order to increase the pressure exerted on the rolls as the stroke or arc of rock is gradually increased, the air cylinder 27 is supplied with air under pressure through the tubing 75 and three pressure regulators 76, 77 and 78. The air is selectively admitted to the cylinder through one of three solenoid air valves 79, 80 and 81, whereof the control coils are arranged for energization

through circuits including the switches 82, 83 and 84 respectively. These switches are closed in sequence by the cam surfaces 85, 86 and 87 on the cylinder or drum 53 as it rotates.

At the end of the rolling operation, the air pressure is released by the operation of the solenoid valve 88. This valve is energized through the circuit including switch 89 which is closed by the cam surface 90. At the end of the cycle, the mechanism is brought to a stop by switch 59 which is momentarily opened by the short cam surface 91. As a result, the return circuit for relays K-5 and K-6 through conductor 58 is momentarily opened so that the holding circuits of both relays are simultaneously broken and the apparatus comes to a stop.

Although the mechanism, as illustrated in Fig. 5, achieves the rocking of the rolls through a reversible electric motor and lead screw arrangement, it may be more convenient for a large scale operation to utilize a suitable hydraulic cylinder whereof the piston is provided with the necessary length of stroke. This is illustrated in Fig. 6 wherein the connecting rods 33 and 34 are pivoted through pin 100 on the upper end of rod 101 of a piston 103 sliding within a cylinder 102. The control system utilized with this arrangement is substantially the same as that illustrated in Fig. 5 with the exception that the reversible solenoid switches K-3 and K-4 are now replaced by a pair of solenoid hydraulic valves 104, 105. Pressurized fluid, for instance water or oil, is supplied to these valves through an inlet tube 106, and the connections to the control coils 107 and 108 are made to the remainder of the control circuits shown in Fig. 5 precisely as for the control coils 64 and 70 of the reversing relays K-3 and K-4. It will be understood that the limit switches K-1 and K-2 are mounted on the upper end of the rod 101 and travel therewith in the same way as with the screw crosshead 32 of Fig. 5.

During the rolling operation, it is desirable that the wire be held vertically between the rolls, that is, normal to the plane through the axes of the rolls, and under a slight tension. The tension is required in order to take up the lengthening of the wire which occurs as the flat portion is rolled into it. A suitable pliers or gripping device for holding the wire is illustrated in Fig. 7 and comprises a pair of rods 109, 110. Rod 110 is rigidly attached to a block 111 serving as a handle, whereas rod 109 is pivotally mounted and is sprung out by means of a hair-spring 112. The lead wire 1 is held across the forward ends of the rods by means of wire loops 113, 114 which are maintained in tension by the coil springs 115, 116. The tension in the loops 113, 114 may be relieved by squeezing the release levers 117, 118 which are pivoted on the rods 109, 110 respectively, and engage the fastening buttons 119, 120 of the wire loops.

In order to hold the lead wire 1 between the rolls 15 and 16, the gripping device with a wire fixed across its ends, is located with its longer dimension parallel to the axes of the rolls and is held in place by suitable means. Then, as the lead wire 1 is gradually lengthened through the formation of the flat portion, rods 109, 110 gradually spread apart and take up the increased length of the wire.

The sequence of operations in the formation of a flat or ribbon portion in a lead wire is illustrated in Figs. 8a through 8d. In Fig. 8a, the lead wire 1 is shown at the beginning of the rolling cycle and is perfectly round throughout

its length. At this time, the air piston 27 exerts the least pressure on the bearing shoes and the rocking arc is the least, as indicated by the relatively short curved arrows 121. Figs. 8b and 8c illustrate intermediate stages in the rolling operation wherein the pressure exerted by the air cylinder 27 has been increased and the rocking arcs have been lengthened, as indicated by the arrows 122 and 123. In Fig. 8d the pressure exerted on the rolls is at the maximum and the arc of rock, indicated by arrows 124, is also at its longest.

It will be understood that the type of foliating operation described above has the advantage that the wire is not merely flattened out from a round or circular cross section to a flat one, but is in addition elongated. Thus the cross sectional area of the wire through the ribbon portion is considerably less than the cross sectional area of the regular or cylindrical portion at either end. This has the advantage of producing a streamlined flow or orientation of the grain structure and results in a much stronger ribbon lead than would be obtained with ribbon leads produced otherwise than through the present longitudinal rolling operation.

The mechanism which has been described may be used for rolling molybdenum and tantalum wire at room temperature. In the case of tungsten, the wire is less ductile and the operation may be assisted by heating the wire, as by passing a current through it, while it is being rolled.

While a certain specific embodiment has been shown and described, it will of course be understood that various modifications may be made without departing from the invention. It will also be understood that the details of the control system and the mechanical means for securing the necessary operation of the rolling members may be changed within the scope of the invention as defined by the appended claims.

What I claim as new and desire to secure by Letters Patent of the United States is:

1. Apparatus for foliating a portion of a wire, comprising a pair of opposed semi-cylinders each having a generally semi-cylindrical axial cavity and a substantially cylindrical roll mounted axially within the cavity, open bearing shoes backing the semi-cylinders, means for forcibly sliding said shoes one towards the other thereby to squeeze a wire located between the rolls transversely to their axes, and means for rocking said semi-cylinders, thereby to draw said wire backwards and forwards between said rolls.

2. Apparatus for forming a one piece ribbon lead having a foliated center portion and cylindrical end portions, comprising a pair of hardened cylindrical rolls composed of a material having a relatively high compressive strength, a pair of opposed semi-cylinders composed of a material of lesser compressive strength and having generally semi-cylindrical axial cavities each receiving one of said rolls and supporting them in mutually facing alignment along parallel axes, a pair of open bearing shoes journaling said semi-cylinders, means forcibly sliding said shoes one toward the other thereby to squeeze a wire located between said rolls transversely to their axes, and means for rocking said semi-cylinders, thereby to draw said wire backwards and forwards between said rolls.

3. Apparatus for forming a one piece ribbon lead having a foliated center portion and cylindrical end portions, comprising a pair of hardened cylindrical rolls composed of a material

having a relatively high compressive strength, a pair of opposed semi-cylinders composed of a material of lesser compressive strength having generally semi-cylindrical axial cavities each receiving one of said rolls and supporting them in mutually facing alignment along parallel axes, a pair of open bearing shoes journaling said semi-cylinders, means forcibly sliding said shoes one toward the other thereby to squeeze a wire located between said rolls transversely to their axes, and means for rocking said semi-cylinders synchronously through gradually increasing arcs, thereby to draw said wire backwards and forwards between said rolls with a gradually increasing stroke.

4. Apparatus for forming a one piece ribbon lead having a foliated center portion and cylindrical end portions, comprising a pair of hardened cylindrical rolls composed of a material having a relatively high compressive strength, a pair of opposed semi-cylinders composed of a material of lesser compressive strength and having generally semi-cylindrical cavities each receiving one of said rolls, open bearing shoes journaling said semi-cylinders, a sliding mounting for said shoes allowing one to be displaced towards the other so that said rolls contact each other along a line parallel to their axes, means for forcibly sliding said shoes together thereby to squeeze a wire located between said rolls transversely to their axes, crank arms attached to said semi-cylinders, a crosshead, rods connecting the outer ends of said cranks to said crosshead, and means for reciprocating said crosshead through a gradually

increasing stroke, thereby to draw said wire backwards and forwards between said rolls with a gradually increasing stroke.

5. Apparatus for foliating a portion of a wire, comprising a pair of opposed semi-cylinders each having a generally semi-cylindrical cavity and a substantially cylindrical roll mounted axially within the cavity, open bearing shoes backing the semi-cylinders, means for forcibly sliding 10 said shoes one towards the other thereby to squeeze a wire located between the rolls transversely to their axes, crank arms attached to said semi-cylinders, a hydraulic cylinder having a reciprocable piston, means linking the outer ends of said cranks to said piston, solenoid hydraulic valves controlling the admission of pressurized fluid to said cylinder, limit switches supported from said piston and connected in a control circuit with said solenoid valves, a plurality of spaced 15 stops cooperable with said limit switches, and means for advancing different stops into position for engagement by said switches at successive strokes of said piston.
